UNITED STATES PATENT OFFICE

JULIUS BECKER, OF CHICAGO, ILLINOIS, ASSIGNOR TO VACUUM CAN COMPANY, A CORPORATION OF ILLINOIS

RHEOSTAT

Application filed October 29, 1928. Serial No. 315,690.

The present invention relates to devices through which electric currents pass to their point of use and which are adapted to vary the characteristics of the current. The object of the present invention is to produce a device of this kind which will give a wide range of variations through a series of extremely small steps; in other words, to produce a device that will permit the current characteristics to be accurately regulated so as best to meet the requirements at any particular time.

In electro-plating, for example, it is common and necessary to employ a rheostat to control the strength of the current, but with the ordinary rheostat it is impossible to secure a nicety of regulation.

In the common type of knife switch rheostats, the resistance is diminished by closing one switch after another, or increased by opening one switch after another, but leaving some resistance continuously in the circuit, making it often impossible to regulate the potential and current density to the desired value, while the adjusting is more or less a drawn out experiment requiring often so much time that before the predetermined value is obtained, the articles to be plated have received too much or too little current and potential, resulting in faulty plate.

These characteristics are much more distinct in the electro-deposition of chromium where high current densities are employed and where an instantaneous regulation to a predetermined value is of necessity for success. Viewed in one of its aspects the present invention may be said to have for its object to produce a rheostat that will permit the resistance to be varied either through large steps or through very small steps, instantaneously, by means of only two movable contact arms, a requirement which is absolutely essential in the electro-deposition of chromium or other noble metals, which require high current densities and a predetermined current value.

Viewed in another of its aspects the present invention may be said to have for its object to produce a rheostat that will permit the resistance to be adjusted in a fraction

of a second to the right current density and potential, resulting in an instantaneous and hair line regulation.

Another advantage is the possibility of utilizing the full generator potential without any additional switches, which would be necessary in the common type of rheostat, to overbridge the resistance which is left in the circuit.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a front view of a rheostat arranged in accordance with my invention, only a fragment of the base being shown; Fig. 2 is a rear view; Fig. 3 is a section on an enlarged scale taken approximately on line 3-3 of Fig. 1; Figs. 4 and 5 are fragmentary sections showing modifications; Fig. 6 is a section taken approximately on line 6-6 of Fig. 5; Fig. 7 is a front or top view of a modified form of main arm for the rheostat; Fig. 8 is a section taken approximately on line 8-8 of Fig. 7; Figs. 9 and 10 are sections taken respectively on lines 9-9 and 10-10 of Fig. 7; Fig. 11 is a detail of a modified form of the auxiliary section of the rheostat; and Fig. 12 is a front or top view of the rheostat arm shown in Fig. 11.

Referring to Figs. 1 to 3 of the drawings, 1 represents a base in the form of a slab of insulating material. Mounted on the front or top of the base are a series of stationary segments 2, 2 arranged in an arc of a circle and spaced apart from each other. Each segment may have on the rear side a post 3 extending through the base and constituting a terminal. The segments may be fastened to the slab by means of screws 4 extending into the same through the base. The segments constitute almost a complete circle, there being left a gap of about the size of one of the segments. In the circular space surrounded by the segments is a metal ring

5 having a wing 6; the wing 6 extending into the gap between the two endmost segments and completing the circle. The wing 6 is provided with a post 7 similar to the posts 3, projecting rearwardly through the base. On the rear side of the base is a second series of segments 8, 8 arranged in a circle and spaced apart from each other. These segments are preferably mounted on a small ringlike slab of insulating material 9 lying against the rear face of the base and secured to the latter in a suitable manner.

A metal post 10 is secured to the front side of the base with its axis at the center of the ring 5. The post is shown as having a flange 11 resting against the front of the base and secured to the base by means of screws 12. On the post is rotatably mounted the main rheostat arm 13. The arm projects in opposite directions from the post, one end resting on the segments 2 and the other end on the ring. A spring 14 between the front side of the arm and a collar 15 on the post, presses the arm into engagement with the segments and ring. At the end of the long end of the rheostat arm is a knob or handle 16 for turning the same. This end of the arm is provided on its inner or under-face with an oil groove 17. A port or passage 18 extends from the groove through the front or outer face of the arm and is there closed by a suitable plug 19. Upon removing the plug, oil may be introduced through the port into the oil groove to lubricate the surfaces over which the long end of the rheostat arm passes. There may be a similar oil groove 20. It is desirable to have the rheostat arm tend to come to rest and be yieldingly held in place whenever it is directly over one of the segments. To this end I have provided a pawl and ratchet device consisting of a series of recesses or depressions 21 distributed about the ring 5 and a spring-pressed plunger 22 in the short end of the rheostat arm.

The segments 2 and the wing 6 may be provided at the periphery with an outwardly-directed web 23 having a flange 24 overhanging the end of the rheostat arm so as to prevent the latter from being lifted off the segments.

Cooperating with the segments 8 on the rear side of the base is a swinging contact 25. In the arrangement shown, this contact is carried on the outer end of a spring arm 26 fixed to the rear end of a shaft 27 that extends lengthwise through the post 10. On the opposite, or front end of the shaft is a handwheel 28 by means of which the shaft may be turned. A suitable pawl and ratchet device may be provided yieldingly to hold the contact piece 25 over any one of the segments with which it cooperates. In the arrangement shown, the segments 8 are pro-

vided on their inner edges with hemispherical recesses 29 adapted to cooperate with a spring-pressed plunger 30 extending radially from the shaft 27.

As best shown in Fig. 2, the posts 3 are connected in any usual or suitable way by means of resistance elements 32 whereas the contact segments 8 are connected by suitable resistance elements 33. One line wire 34 is connected to a post 3 at one end of the series while the other line wire 35 is connected to the post 7. The line wire 34 is also connected to one of the segments 8 through a resistance 36. It will thus be seen that a large variation in the resistance may be produced by turning the main arm of the rheostat and, after it has been brought to rest on any of the main contact segments, a finer regulation may be effected by turning the auxiliary arm. The total number of adjustments that may be made is therefore approximately equal to the number of the main segments multiplied by the number of the auxiliary segments. As a result, the current values may be varied by extremely small steps.

In Fig. 4 the rheostat arm 13^a has an L-shaped foot 40 fitting into an arc-shaped groove 41 of similar shape in the contact segment 2^a.

In Figs. 5 and 6, the rheostat arm 13^b has a lug 42 projecting down into a wide arc-shaped groove 43 in the segment 2^b. In the groove, beside the lug, is a shoe 44 between which and the lug are arranged springs 45, to insure good contact between the arm and the segment.

In Figs. 7 to 10 I have illustrated a modified form of main rheostat arm. The arm, 13^c, has in one end a square or rectangular hole 50 extending through the same. In this hole is slidably mounted a contact brush in the form of a block 51 composed of copper gauze, brass gauze, copper-carbon mixture, solid brass or copper, or other suitable conducting material. On top of the arm, at some distance above the block, is a stationary cross-piece 52. Between the cross-piece and the contact block are springs 53. A pigtail 54 has one end secured to the block, while its other end is secured to the arm. In the opposite end of the arm are two holes 55, 55. Slidably mounted in these holes are brushes or contacts in the form of blocks 56, 56, similar to the block 51. A curved leaf spring 57 is secured at the middle to the arm at a point between the two brushes by means of a screw 58 or the like; the ends of the spring pressing down on the blocks. The brushes are connected to the arm by suitable pigtails 59.

In Figs. 11 and 12 there is illustrated a modified form of auxiliary contact arm. On the shaft 27 is a sleeve 60 from which projects a radial arm 61 whose outer end is

in the form of an open frame 62. In the opening in the frame is a slidable contact block or brush 63. Secured at one end to the end of the shaft, by a screw 64 or otherwise, is a spring finger 65 whose free end presses on the block to hold it in contact with the segments 8. A pigtail 66 extends from the brush to the shaft, the screw 64 serving the double purpose of securing the spring finger and the pigtail to the shaft.

It will thus be seen that I have produced a simple and novel rheostat by means of which fine adjustment of the resistance can be made over a wide range by means that permit the use of a comparatively small number of resistance elements to produce a much larger number of adjustments. It will also be seen that the movable arms of the rheostat become yieldingly locked when they are brought to rest properly positioned over the cooperating stationary contacts. Also, in all forms of my invention, the movable contact elements are yieldingly pressed into engagement with the stationary elements and the cooperating surfaces between the contacts are effectively lubricated so that the rheostat may at all times be easily operated.

I claim:—

1. In a rheostat, a base of insulating material, a rotatable shaft extending through said base, a series of main stationary contacts arranged in an arc about said shaft on one side of the base, a series of auxiliary stationary contacts arranged in an arc about said shaft on the other side of the base, a contact mounted on said shaft in position to ride over the auxiliary contacts when the shaft is rotated, and a main contact arm mounted to rotate about said shaft, the main arm engaging with said main stationary contacts.

2. In a rheostat, a base of insulating material, a post fixed to and projecting from the base, two sets of stationary contact elements mounted on opposite sides of the base in arcs of circles having their centers at the axis of the post, a main contact arm rotatable on the post and cooperating with one set of stationary contact elements, a shaft extending through the post and rotatable therein, a contact arm on one end of the post cooperating with the second set of stationary contact elements, and an operating handle on the opposite end of the shaft.

3. In a rheostat, a base of insulating material, a metal ring overlying and secured upon the base, a radial wing projecting from the periphery of the ring, a series of stationary contact elements spaced apart from each other and from said wing and forming with the latter an articulated ring spaced apart from the aforesaid ring, a rotatable contact arm extending radially of said rings and engaging with the latter,

there being recesses in the top of the central ring, and a spring-pressed dog on said arm in position to engage with one after another of said recesses as the arm is rotated, a terminal on said wing, a second terminal, and resistance elements connecting said second terminal with said stationary contact elements.

4. In a rheostat, stationary contacts, a movable contact mounted to slide over the stationary contacts and in engagement therewith, said movable contact having in its working face a groove for receiving a lubricant, and there being a passage leading from said groove to the opposite face of the movable contact to receive lubricating material and deliver it to said groove.

In testimony whereof, I sign this specification.

JULIUS BECKER.
